[57] CLAIM

The ornamental design for a medical nail, as shown and described.

DESCRIPTION

FIG. 1 is a perspective view of a medical nail showing my new design;

FIG. 2 is a perspective view thereof rotated 180° on its longitudinal axis;

FIG. 3 is a perspective view from the opposite end thereof;

FIG. 4 is a front side elevational view thereof;

FIG. 5 is a rear side elevational view thereof;

FIG. 6 is an end view thereof taken from the left end of FIG. 1; and

FIG. 7 is an end view thereof taken from the right end of FIG. 1.

The two sides adjacent that shown in FIG. 4 are duplicates thereof.
